[57] ABSTRACT

A detergent composition having inherent softening properties consisting essentially of a builder salt and a detergent selected from the group consisting of water-soluble sulfosuccinates of polyhydroxy tertiary amines having the structural formula:

wherein R_1 is a monovalent hydrocarbon radical of 8 to 24, preferably 10 to 20 carbon atoms; R_2 is an alkyl or alkylol radical containing 1 to 6 carbon atoms, and R_3 is an alkylol radical containing 1 to 6 carbon atoms, and salts thereof. The reaction mixture consists of sulfonated mono-, di-, and/or tri-esters, depending on the number of reactive hydroxyl groups in the alcohamine and the amount of dicarboxylic acid utilized. Since the aforedefined sulfonated esters and salts thereof uniquely possess both detergency and softening properties, they may constitute the sole detergent ingredient in the composition, although the presence of other detergents is not precluded.

DETERGENT-SOFTENER COMPOSITIONS CONTAINING SULFOSUCCINATES OF POLYHYDROXY TERTIARY AMINES

This invention relates to novel detergent compositions containing sulfosuccinates of 2-hydroxy alkyl-⁵
tertiary alcohol amines and salts thereof. It has been discovered that said compounds are useful surface active agents and are substantive to a variety of fibrous materials. Thus, they may be used as emulsifiers, solubilizing agents for lipophilic materials, wetting agents, detersives and softeners for textiles and hair.¹⁰

Since the introduction of commercial synthetic organic detergents and emulsifiers to replace the conventional water-soluble higher fatty acid soaps, much research work has been performed in an effort to improve such compounds and compositions including them, with the object of obtaining better and more convenient laundering of textiles. As a result, a wide variety of types of surface active agents and detergents have been produced and many such compositions have been manufactured commercially and have been introduced to the market place. As better products were made, the goals set for researchers on detergency were increased and the properties of the desired products were such as to have been thought impossible of attainment only a few years before. Although the cleaning function of surface active materials is still very important and products which clean better than competitive compounds are always in demand, additional attributes of cleaning compounds were desired. For example, with the increasing importance of cold water washing, detergent compositions were desired which would be capable of successfully cleaning and whitening textiles and laundry in cold water, as well as in hot water. Such washing capability is of importance in making a product acceptable for the washing of wool and other shrink-sensitive materials. In addition, softening agents have been found to be a desirable, and in some instances, a necessary ingredient in the washing of textiles. However, because of the incompatibility of softeners and detergents, it has been necessary to utilize the textile softener in the final rinse as a separate step in a washing cycle. The objections to this procedure are obvious; one must be present during the washing cycle and few washing machines include devices for the addition of softeners in the final rinse.

Accordingly, it has long been the desire of the detergent industry to develop a detergent composition possessing detergency and fabric softening characteristics and compatibility with conventional water-soluble detergency builder salts.

It has now been discovered in accordance with the present invention that detergent compositions comprising certain sulfosuccinates of 2-hydroxyalkyl tertiary alcoholamines and salts thereof in conjunction with water-soluble detergency builder salts possess all of the characteristics desired. Thus, in this respect, it has been discovered that the aforedefined sulfonated esters possess not only exceptional detergency characteristics, but possess fabric softening characteristics and is completely compatible with conventional water-soluble detergency builder salts. Thus, the combination of the present invention comprising the sulfosuccinates of 2-hydroxy alkyl alcoholamines and the conventional water-soluble detergency builder salts can be produced both as a homogeneous single phase liquid

detergent composition or can be conveniently prepared in the form of bars, flakes, granular or tableted granular compositions.

Accordingly, a principal object of the present invention is to provide novel detergent compositions wherein the detergent component thereof possesses, in addition to detergency characteristics, fabric-softening characteristics, and is completely compatible with conventional water-soluble detergency builder salts.

Still further objects and advantages of the novel detergent composition of the present invention will become more apparent from the following more detailed description thereof.

In accordance with the present invention, it has now been discovered that sulfosuccinates of polyhydroxy tertiary amines and salts thereof possess the unusual characteristics of excellent detergency and fabric softening ability in addition to complete compatibility with water-soluble detergency builder salts conventionally employed in detergent compositions. Accordingly, the present invention is directed to such detergent compositions based upon aforesaid sulfosuccinates of 2-hydroxy alkyl tertiary alcoholamine and water-soluble detergency builder salts.

25 The sulfosuccinates of 2-hydroxyalkyl tertiary alcohols amines employed in the novel detergent compositions of the present invention, possess both detergency and fabric softening ability and consist predominantly of the mono-ester having the formula:

wherein R_1 is a monovalent hydrocarbon radical of 8 to 24 and preferably 10 to 20 carbon atoms, R_2 is an alkyl or alkylol radical of 1 to 6 carbon atoms, R_4 is a divalent hydrocarbon radical of 1 to 6 carbon atoms ($R_4-OH=R_3$); R_5 is a divalent hydrocarbon radical (residue of the sulfonated dicarboxylic acid), X is hydrogen or a salt-forming element or radical. If X is an element, it is preferred that it should be an alkali metal such as potassium, sodium and lithium or other suitable salt-forming metal. If X is a radical, it is preferred that such be ammonium, alkylamine or alkanolamine, either mono-, di- or tri-alkylamine or mono-, di-, or tri-alkanolamine, in which the alkyl and alkanol groups of the salt-forming amines are of 2 to 4 carbon atoms, preferably 2 to 3 carbon atoms.

55 The novel sulfonated esters of the present invention can be prepared by a two step synthesis comprising the esterification of the polyhydroxy tertiary amine with an unsaturated dicarboxylic acid and subsequently sulfonating the ester with an alkali metal sulfite salt or by other suitable sulfonating means. More specifically, the ester may be formed by reacting the unsaturated dicarboxylic acid or preferably the anhydride thereof with a polyhydroxy tertiary amine having the structure:

65 wherein R_1 is a monovalent hydrocarbon radical of 8 to 24 and preferably 10 to 20 carbon atoms, R_2 is an alkyl or hydroxyalkyl radical containing 1 to 6 carbon

atoms, R_3 is a hydroxy alkyl radical containing 1 to 6 carbon atoms. Examples of

radicals of this class are:

and related compounds in which the radicals contain more carbon atoms than in the formula shown above, e.g., radicals of di(isopropanol)amine, N-methyl-N-isopropanol-amine, N-ethyl-N-ethanolamine, N-ethyl-N-isopropanolamine, N-propyl-N-ethanolamine, N-propyl-N-isopropanolamine, N-methyl-N-hydroxyethoxyethylamine, N-butyl-N-hydroxyethoxyethylamine, N-cyclohexyl-N-hydroxyethoxyethylamine, N-butyl-N-ethanolamine, di(hydroxyethoxyethyl)amine, mono(hydroxyethoxyethoxyethyl)amine, N-hydroxyethoxyethoxyethyl-N-methylamine, N-hydroxyethyl-N-hydroxyisopropylamine, N-benzyl-N-hydroxyethylamine, or N-cyclohexyl-N-2-hydroxy-2-phenylethylamine.

The polyhydroxy tertiary amines are known compounds which may be prepared by condensing secondary alcoholamines with long chain epoxides. A typical example of an amine/epoxide reaction is the preparation of 2-hydroxyalkyl-diethanolamine.

The unsaturated dicarboxylic acid anhydride may be maleic anhydride or a substituted maleic anhydride:

The reaction is predominantly in accordance with the following equations:

wherein the R radicals are as aforedefined, and equimolar amounts of reactants are used. The sulfonation step adds the sulfonate group to the unsaturated acid radical at the point of unsaturation as illustrated by the following equations when utilizing maleic anhydride:

3.

15

The alcoholamine has at least two hydroxyl groups, one in the long chain resulting from the epoxide ring opening and one or more from the original alcoholamine. When utilizing equimolar amounts of reactants, the primary hydroxyl is preferentially esterified into the mono-ester, since it is the least sterically hindered and therefore most reactive group. However, when more than one mole of the acid anhydride is used, the other hydroxyl radicals react to form the di-ester, tri-ester, etc. and mixtures thereof. Similarly, the number of hydroxyl groups in the alcoholamine is determinative of the formation of the mono-, di-, or tri-esters.

4.

5.

6.

40

The sulfonated esters formed in accordance with instant invention have one free carboxyl group and one sulfonated group for every esterified carboxyl radical as shown by the following structural formulae:

mono-ester:

di-ester:

or

tri-ester:

60

65

The esterification of the 2-hydroxyalkylalcoholamines with the unsaturated dicarboxylic acid anhydride is an exothermic reaction which can be carried out in aprotic solvent, ether, chloroform or acetone, but it can also be carried out neat. The latter method is preferable as an industrial process, since no solvent is involved, thereby not giving any by-products. The powdered acid anhydride (e.g., maleic anhydride) is added gradually to the liquid alcoholamine which is held at a temperature of about 100°C. When the reaction is over, the product is cooled and subsequently sulfonated by the addition of the ester to an aqueous solution of a sulfite salt. The mixture is heated to about 50°-90°C with agitation for a period of about 30-60 minutes. A clear, viscous solution is obtained. The final product may be freeze dried and is obtained in the form of a solid, which is insoluble in acetone, ether, etc., but very soluble in water. When utilizing a solvent during the esterification step, the reactants are first dissolved therein and the solution refluxed until the reaction is complete. Evaporation of the solvent yields a resin-like, waxy product, insoluble in water, which is subsequently sulfonated as above. When utilizing the unsaturated dicarboxylic acid in lieu of the anhydride, esterification is controlled so that only one mole of water is removed per mole of alcohol. Termination of esterification at this point ensures the formation of mono-, di-, and/or tri-esters as defined in copending application Ser. No. 205,395, filed Dec. 6, 1971 in the name of Bjorn Sundby and prevents the production of a polymeric linear ester. The esterification reaction may be controlled by conventional methods of cooling or by other suitable means.

The products obtained are usually clear, viscous solutions of sulfonated mono-, di-, tri-esters and mixtures thereof, readily soluble in water. The sulfonated mono-, di-, and tri-esters can be readily separated and purified by chromatographic techniques in the usual manner. However, separation is not necessary. The mixture of mono-, di-, and/or tri-esters can be used as the effective detergent, due to their combined property of detergency and fabric conditioning (softening, anti-static, etc.). The high viscosity solutions that some members of this series form render them particularly useful in shampoos.

Examples of sulfonated esters in accordance with the present invention include:

sulfosuccinate of N-(2-hydroxy hexadecyl) diethanolamine

sulfosuccinate of N-(2-hydroxy octadecyl) diethanolamine

sulfosuccinate of N-(2-hydroxy octadecyl) diisopropanolamine

sulfosuccinate of N-(2-hydroxy octadecyl) diglycolamine

sulfosuccinate of N-(2-hydroxy octadecyl) methyl-ethanolamine

sulfosuccinate of N-(2-hydroxy dodecyl) diethanolamine

sulfosuccinate of N-(2-hydroxy dodecyl) diisopropanolamine

sulfosuccinate of N-(2-hydroxy dodecyl) diglycolamine

sulfosuccinate of N-(2-hydroxy dodecyl) methylethanolamine

sulfosuccinate of N-(2-hydroxy tetradecyl) diethanolamine

Further examples of sulfonated esters of 2-hydroxyalkyl tertiary alcoholamine and processes for producing the same can be found in co-pending application Ser. No. 205,395, filed Dec. 6, 1971 in the name of Bjorn Sundby.

The novel sulfonated esters of the present invention, in addition to possessing excellent detergency and fabric softening properties, have been found to be compatible with the various detergent builders and other additives conventionally employed in detergent compositions. Accordingly, it is possible to formulate a detergent composition based on the sulfonated ester of instant invention as the detergent and fabric softener.

In addition to the aforedefined sulfonated esters or salts thereof, the novel detergent compositions of the present invention may contain one or more water-soluble detergency builder salts either of the organic or the inorganic type.

Examples of water-soluble inorganic detergency builder salts are alkali metal carbonates, bicarbonates, phosphates, polyphosphates, sulfates, borates and silicates, etc. Specific examples of such salts are sodium, potassium and lithium tripolyphosphates, carbonates, pyrophosphates, orthophosphates and hexamethaphosphates; sodium, potassium and lithium sulfates; sodium, potassium and lithium silicates; sodium carbonate, bicarbonate, sequicarbonate; sodium tetraborate and mixtures thereof. Examples of organic alkaline detergency builder salts are (1) alkali metal amino polycarboxylates (e.g., sodium and potassium ethylenediamine-tetraacetates, N-(2-hydroxyethyl)-ethylenediaminetriacetates, nitrilo triacetates, and N-(2-hydroxyethyl)-nitrilo diacetates); (2) alkali metal salts of phytic acid (e.g., sodium and potassium phytates — See U.S. Pat. No. 2,739,942); (3) water-soluble salts of ethane-1-hydroxy-1, 1-diphosphonate (e.g., the trisodium and tripotassium salts — See U.S. Pat. No. 3,159,581); (4) water-soluble salts of methylene diphosphonic acid (e.g., trisodium and tripotassium methylene diphosphonate and the other salts described in U.S. Pat. No. 3,213,030); (5) water-soluble salts of substituted methylene diphosphonic acids (e.g., trisodium and tripotassium ethylidene, isopropylidene, benzylmethylidene, and halomethylidene diphosphonates); (6) water-soluble salts of polycarboxylate polymers and copolymers (e.g., polymers of itaconic acid, aconitic acid, maleic acid; mesaconic acid; fumaric acid; methylene malonic acid; and citric acid and copolymers with themselves and other compatible monomers such as ethylene); and mixtures thereof. Similarly, mixtures of organic and inorganic builder salts is also contemplated by instant invention.

In the detergent composition of the present invention, the sulfonated ester or salt thereof is generally employed in an amount of from about 5 to 30% by weight of the total composition. While the water-soluble detergency builder salts comprise from about 70 to about 95% by weight of the total composition. Preferably, the sulfonated dicarboxylic acid-polyhydroxy tertiary amine ester comprises about 10-25% by weight while the detergent builders comprise from about 75-90% of the total composition.

The detergent compositions of this invention can contain any of the usual adjuvants, diluents and additives; for example, anionic, nonionic, ampholytic, cationic or zwitterionic detergents, perfumes, anti-tarnishing agents, anti-redeposition agents, bacterio-

static agents, dyes, fluorescers, suds builders, suds depressors, enzymes and the like, without detracting from the advantageous properties of the composition. Examples of anionic detergents are sodium xylene sulfonate, sodium toluene sulfonate, sodium coconut soap, sodium dodecyl benzene sulfonate and potassium tallol alkyl sulfate. Examples of nonionic detergents are dodecyl-dimethylamine oxide and the condensation product of coconut fatty alcohol with 5.5 moles of ethylene oxide. An example of a zwitterionic detergent is 3-(N-N-dimethyl-N-hexadecylammonio)-2-hydroxypropane-1-sulfonate. An example of an amphoteric detergent is sodium 3-dodecylamino-propionate. An example of a cationic detergent is cetyltrimethylammonium bromide.

While the detergent compositions of the present invention are excellent compositions for all types of cleaning operations, the compositions of the present invention are extremely effective for the cleaning of textiles as in a conventional laundry or washing machine. Thus, the detergent compositions of the present invention can be effectively used for laundering fabrics in water having a temperature of from about 60° F to about 212° F, the detergent composition of the present invention exhibiting unusually effective detergency and fabric softening characteristics in both cold and hot water. Preferably, the step of washing the fabrics with the detergent composition of the present invention is followed by rinsing and drying of the fabric. The detergent composition concentration in the wash solution should range from about 0.05% to about 0.5% by total weight, and the detergent composition should be added so as to provide an effective detergent and fabric softening amount of the sulfonated esters of 2-hydroxyalkylalcoholamine of at least 0.005%.

In washing fabrics, the addition of the fabrics and the detergent composition can be conducted in any suitable conventional manner. Thus, for example, the fabrics can be added to the container or washer either before or after the washing solution is added. The fabrics are then agitated in the detergent solution for varied periods of time, a wash cycle of from 8 to 15 minutes being generally used in the washing cycle of an automatic agitator type washer. As stated above, following the washing of the fabrics, the detergent composition is drained off of the fabrics and the fabrics are rinsed in substantially pure water. Here again, as a matter of choice, the fabrics can be rinsed as many times as desired. After rinsing of the fabrics, the fabrics are dried first by spinning and then by contact with the air as in conventional hanging of the fabrics on a clothesline or in an automatic dryer type system.

In the preparation of the novel detergent compositions of the present invention, generally, the organic detergent and water softening component as well as the builders and any minor ingredients are incorporated into the composition prior to its conversion into the final product form, e.g., detergent granules, flakes, bar, etc. However, the individual components of the novel detergent composition of the present invention can be added in the form of particles or directly as a liquid to produce a liquid detergent composition.

Various embodiments of the present invention will now be illustrated by reference to the following specific examples. It is to be understood, however, that such examples are presented for purposes of illustration only, and the present invention is in no way to be deemed as limited thereby.

EXAMPLE I

The instant novel sulfonated esters and salts thereof were tested for their detergency properties as well as their efficacy as fabric softeners. The Spangler soil detergency tests were run using an aqueous solution containing 1.5 g. of detergent/liter water (0.15% product concentration), said detergent comprising 15% of the compound to be tested, 35% sodium tripolyphosphate and 50% sodium sulfate (based on dry ingredients), in soft and hard water at both 70° F and 120° F. Three Spangler soil swatches were washed 10 minutes in a Tergotometer at 100 RPM, rinsed 5 minutes, and dried. The ingredients were dry-blended by conventional methods and added to the aqueous system in the Tergotometer.

TABLE I

	Compound	ΔRd (Soil Removal)			
		70°F	120°F	NB-TAP	300 PPM
20	1. Disodium sulfosuccinate of N-(2-hydroxyhexadecyl) diethanolamine	12.3	11.2	17.6	12.5
25	2. Control-Linear tridecyl benzene sulfonate	16.2	9.9	21.0	12.2
30	3. Disodium sulfosuccinate of N-(2-OHC ₁₆) diethanolamine	12.8	10.2	17.1	13.5
35	4. Disodium sulfosuccinate of N-(2-OHC ₁₆) methyl ethanolamine	14.3	10.9	13.6	13.0
	5. Disodium sulfosuccinate of N-(2-OHC ₁₆) diisopropanolamine	14.4	11.2	13.9	16.3

EXAMPLE II

Similarly, the test for softening effect on cotton materials is run by washing one terry cloth towel in 17 gallons of NB tap water at 120° F and air drying. The softness is rated on a scale of 1 to 10, with 1 indicating no softness and 10 representing maximum softness.

TABLE 2

	Softness Ratings	45	
		1. 10g AI sulfosuccinate of N-(2-hydroxy hexadecyl) diethanolamine, 40g Pentasodium Tripolyphosphate (NaTPP)	7
50	2. 10% sulfosuccinate of N-(2-hydroxy octadecyl) methylmethanolamine 40% NaTPP	10	
	3. 10% sulfosuccinate of N-(2-hydroxy octadecyl) diisopropanol amine, 40% NaTPP	10	
	4. 5g AI sodium sulfosuccinate in (1), 10g AI linear dodecyl benzene sulfonate, 40g NaTPP	5	
	5. 30g sulfosuccinate of N-(2-hydroxyoctadecyl) diethanolamine	10	
55	6. Linear tridecyl benzene sulfonate	1	

The results shown above indicate an unexpectedly excellent detergency in hard and soft water, both cold and hot, as compared to commercial detergent linear tridecyl benzene sulfonate. In addition to possessing excellent detergency properties, instant sulfonated esters exhibit excellent fabric softening characteristics, not possessed by the control. Similar results are obtained with other sulfonated esters of 2-hydroxy alkyl tertiary alcohol amines of instant invention and salts thereof.

EXAMPLE III

Other typical detergent-softening compositions include:

80% sodium tripolyphosphate, and
 20% a. sulfosuccinate of N-(2-OH dodecyl) methyl-
 ethanolamine
 b. sulfosuccinate of N-(2-OH octadecyl) methyleth-
 anolamine
 c. sulfosuccinate of N-(2-OH dodecyl) diisopropano-
 lamine
 d. sulfosuccinate of N-(2-OH octadecyl) diisopropano-
 lamine
 e. sulfosuccinate of N-(2-OH dodecyl) diethanol-
 amine
 f. sulfosuccinate of N-(2-OH octadecyl) diethanol-
 amine
 g. sulfosuccinate of N-(2-OH dodecyl) diglycolamine
 h. sulfosuccinate of N-(2-OH octadecyl) diglycolamine

EXAMPLE IV

40 g sodium tripolyphosphate
 5 g disodium sulfosuccinate of 2-hydroxy hexadecyl
 diethanolamine
 10 g linear tridecyl benzene sulfonate.
 Fabric treated with an aqueous solution of the above
 ingredients in accordance with the method in Example
 I, gave a softness rating of 5.

EXAMPLE V

Repeat Example IV, but omit the linear tridecyl ben-
 zene sulfonate and increase the sulfosuccinate content
 to 10 g.

The elimination of the sulfonate and an increase in
 the sulfosuccinate yielded a superior softness rating, n-
 amely 7.

EXAMPLE VI

The sulfosuccinate of Example V was acidified with
 lactic acid. Fabric was washed with an aqueous solution
 thereof, rinsed and dried, in accordance with the
 procedure in Example 1, resulting in a softness rating
 of 10.

EXAMPLE VII

20 g of an 8% solution of disodium sulfosuccinate of
 N-(2-hydroxyoctadecyl) diethanolamine.

10 g of an 8% solution of 2-heptadecyl-1-methyl-1-
 [(2-stearoylamido)ethyl] imidazolinium methyl sulfate.

The two ingredients were blended and isopropanol
 added to form a clear solution. Fabric treated with this
 solution exhibited a softness rating of 10.

EXAMPLE VIII

The composition of Example VII was acidified with
 lactic acid, thereby forming a clear, viscous liquid.
 Fabric treated therewith exhibited excellent softness.

EXAMPLE IX

15 g of an 8% solution of disodium sulfosuccinate of
 N-(2-hydroxyoctadecyl) diethanolamine

15 g of an 8% solution of N-(2-hydroxy C₁₆₋₁₈) sarco-
 sine.

The two ingredients were acidified with lactic acid,
 forming a translucent, viscous liquid. Fabric treated
 herewith exhibited excellent softness and whiteness.

EXAMPLE X

Other typical detergent-softening compositions in-
 clude:

40% sodium tripolyphosphate

45% sodium sulfate
 15% disodium sulfosuccinate of N-(2 hydroxyoctade-
 cyl) diisopropanolamine.

EXAMPLE XI

40% sodium tripolyphosphate
 45% sodium sulfate
 15% disodium sulfosuccinate of N-(2-
 hydroxyoctadecyl) methyl ethanolamine.

EXAMPLE XII

30 g of an 8% aqueous solution of disodium sulfosuc-
 cinate of N-(2-hydroxyoctadecyl) diethanolamine
 tested in accordance with the procedure of Example
 2 gave a softness rating of 10.

At room temperature, this composition was a clear,
 1-phase, moderately viscous liquid which may be used
 in the wash cycle with known commercial laundry de-
 tergents as both a softener and detergency booster.

The present invention has been described in conjunc-
 tion with various illustrations and embodiments
 thereof set forth in the specification. However, it is evi-
 dent that equivalents may be substituted for the pres-
 ent compounds and procedural steps, without depart-
 ing from the principles of this invention or the spirit
 thereof. Those of skill in the art will recognize what
 equivalents and substitutes are also within the scope of
 the present disclosure.

What is claimed:

1. A detergent composition having inherent softening
 properties comprising about 5-30% by weight of water
 soluble sulfosuccinate esters of polyhydroxy tertiary
 amines, said amines having the structural formula:

wherein R₁ is an alkyl radical of 8 to 24 carbon atoms,
 R₂ is an alkyl or alkylol radical of 1 to 6 carbon atoms,
 and R₃ is an alkylol radical of 1 to 6 carbon atoms or
 the alkali metal, ammonium, alkyl amine and alkanol
 amine salts thereof, the alkyl and alkanol groups of
 said amines containing from 2 to 4 carbon atoms, and
 about 70-95% water soluble builder salts, said water
 soluble sulfosuccinate esters being selected from the
 group consisting of mono, di and trisulfosuccinates
 containing respectively 1, 2 and 3 carboxyl groups and
 respectively 1, 2 and 3 sulfo groups, and mixtures
 thereof.

2. A detergent composition in accordance with claim
 1, wherein the sulfonated mono-ester has the formula:

wherein R₁ and R₂ are as defined above, R₄ is an alkyl-
 ene radical of 1 to 6 carbon atoms, R₅ is an ethylene
 radical and X is hydrogen or salt-forming element or
 radical selected from the group consisting of alkali
 metal, ammonium, alkyl amine and alkanol amine, the
 alkyl and alkanol groups of said amines containing
 from 2 to 4 carbon atoms.

3. A composition in accordance with claim 1, which
 contains disodium sulfosuccinate of N-(2-hydroxy hex-
 adecyl)-diethanolamine.

4. A composition in accordance with claim 1, which
 contains sulfosuccinate of N-(2-hydroxyoctadecyl)
 methylethanolamine.

5. A composition in accordance with claim 1, which

contains sulfosuccinate of N-(2-hydroxyoctadecyl) diisopropanolamine.

6. A method of simultaneously cleaning and softening textiles which comprises laundering said textiles in an aqueous bath containing the composition of claim 1.

7. A method in accordance with claim 6, wherein the detergent composition constitutes about 0.05-0.5% by weight of the aqueous bath.
